CLAIM

The ornamental design for a veress needle cap, as shown and described.

DESCRIPTION

FIG. 1 is a perspective view of a veress needle cap showing our new design;

FIG. 2 is a frontal view of the veress needle cap shown in FIG. 1;

FIG. 3 is a rear view of the veress needle cap shown in FIG. 1;

FIG. 4 is a right-side view of the veress needle cap shown in FIG. 1;

FIG. 5 is a left-side view of the veress needle cap shown in FIG. 1;

FIG. 6 is a top view of the veress needle cap shown in FIG. 1;

FIG. 7 is a bottom view of the veress needle cap shown in FIG. 1; and,

FIG. 8 is a side view of the veress needle cap shown in FIG. 1 in use and positioned over an end portion of a veress needle.

The dashed broken lines shown in the drawings illustrate portions of the veress needle cap that forms no part of the claimed design.

1 Claim, 8 Drawing Sheets
